[57] ABSTRACT

Gasoline containing ether amines as carburetor deter-
gents; and ether amine additive concentrates.

7 Claims, No Drawings

1
GASOLINE ADDITIVE

BACKGROUND OF THE INVENTION

The invention involves the use of certain ether amines as carburetor detergents.

Deposits which form on various internal parts of internal combustion engine carburetors are undesirable. These deposits tend to reduce the efficiency of the carburetor and ultimately the performance of the engine itself. Gasoline additives which reduce or remove these undesirable deposits are available. These additives are commonly referred to as carburetor detergents.

Ether amines having the formula

where R is sec-alkyl or cycloalkyl, R' is hydrogen, sec-alkyl or cycloalkyl, R'' is alkylene, and R''' is alkyl or hydroxyalkyl are known (U.S. Pat. No. 3,478,096). They are shown to be useful in distillate fuels, including gasoline, as stabilizers (U.S. Pat. No. 3,637,358).

It has now been discovered that certain other ether amines are effective carburetor detergents.

SUMMARY OF THE INVENTION

Gasoline containing a carburetor detergent amount of ether amine selected from

- i. $\text{R}-\text{O}-\text{L}-\text{NH}_2$
- ii. $(\text{R}-\text{O}-\text{L})_2\text{NH}$, and
- iii. mixtures containing (i) and (ii),

wherein R is selected from C_1-C_{40} alkyl groups, C_6-C_{40} aryl groups, and C_3-C_{41} alkenyl groups, and L is C_2-C_8 alkylene; additive concentrates suitable for blending into gasoline containing said ether amine detergent.

DESCRIPTION OF THE PREFERRED EMBODIMENTS

An embodiment of the present invention is gasoline containing a carburetor detergent amount of ether amine selected from

- i. $\text{R}-\text{O}-\text{L}-\text{NH}_2$ I
- ii. $(\text{R}-\text{O}-\text{L})_2\text{NH}$ II
- iii. mixtures containing I and II.

Preferred gasoline compositions contain ether amine wherein L is $-\text{CH}_2-\text{CH}_2-\text{CH}_2-$. More preferred gasoline compositions contain ether amine wherein L is $-\text{CH}_2-\text{CH}_2-\text{CH}_2-$ and R is C_4-C_{30} alkyl. More preferred gasoline compositions contain said ether amine mixture where L is $-\text{CH}_2-\text{CH}_2-\text{CH}_2-$ and R is C_8-C_{30} alkyl.

The group R in useful ether amines has from one to about 40 carbon atoms and includes aryl, alkenyl and alkyl groups. These groups may be substituted or unsubstituted; branched or linear; cyclic or acyclic.

The aryl R groups include alkaryl as well as aralkyl groups. Illustrative examples of suitable aryl R groups are phenyl, di-heptadecylphenyl, tolyl, tert-butylphenyl, 1,3,5-trimethylphenyl, naphthyl, biphenyl, benzyl, 6-phenyl-n-hexyl and the like.

Illustrative examples of suitable C_3-C_{40} alkenyl R groups are propenyl, octadecenyl, tetracontenyl, oleyl, indenyl, linoleyl, decenyl, pentacosenyl and the like.

Examples of useful alkyl R groups are methyl, tetracetyl, isobutyl, 2-ethylhexyl, 2,4-demethylheptyl,

2,4,6-trimethylnonyl, undecyl, tricosyl, cyclohexyl, dodecyl and the like.

Preferred R groups are C_4-C_{30} alkyl groups. Representative examples of these groups are n-butyl, n-eicosyl, decyl, isopentyl, sec-butyl, ethylcyclohexyl, cyclopentyl, dodecyl, pentadecyl, nonadecyl, octacosyl and the like.

More preferred alkyl R groups have 8 to 30 carbon atoms — still more preferred alkyl R groups are C_8-C_{24} . Illustrative of this last group are tetradearyl, eicosyl, 2-ethylhexyl, tetracosyl and the like.

The group L in the present ether amines is C_2-C_8 alkylene. An alkylene group is a hydrocarbyl radical which has the general formula $-\text{C}_n\text{H}_{2n}-$. Representative alkylene groups are —

and the like.

Illustrative examples of useful ether amines are $\text{CH}_3-\text{O}-(\text{CH}_2)_8-\text{NH}_2$, $(\text{C}_{40}-\text{H}_{81}-\text{O}-\text{CH}_2-\text{CH}_2-\text{CH}_2-\text{NH}_2)_2$, $\text{H}_2\text{C}=\text{CH}-\text{CH}_2-\text{O}-\text{CH}_2-\text{CH}_2-\text{NH}_2$, 2-benzylxy-n-propylamine, $[\text{C}_3\text{H}_{11}-\text{O}-(\text{CH}_2)_5]+\text{NH}$, 4-cyclohexyloxy-n-butylamine, $\text{C}_{17}\text{H}_{34}-\text{O}-(\text{CH}_2)_6-\text{NH}_2$, 1,2-dimethyl-2-octadecyloxyethylamine, di(2-phenoxyethyl)amine, 4-tricosyloxy-n-butylamine, 6-(3-phenyl-n-propyloxy)-n-hexylamine, $[\text{C}_{16}\text{H}_{31}-\text{O}-\text{CH}-(\text{CH}_3)-\text{CH}-(\text{CH}_3)_2]+\text{NH}$ and the like and mixtures thereof. These mixtures include mixtures of only the primary ether amines, only the secondary ether amines or preferably mixtures containing both the primary and secondary amines.

More preferred ether amines of Formulae I and II are those where L is $-\text{CH}_2-\text{CH}_2-\text{CH}_2-$ and R is as exemplified above. In other words, R substituted ethers of n-propyl amines are more preferred.

Most preferred ether amines are the Formulae I and II compound (and mixtures containing both) where L is $-(\text{CH}_2)_3$ and R is hydrocarbon alkyl in C_1-C_{40} range, preferably C_4-C_{30} range, and more preferably C_8-C_{24} range.

Illustrative examples of most preferred amines are 3-methoxy-n-propylamine, 3-triacontyloxy-n-propylamine, 3-cyclohexyloxy-n-propylamine, 3-tetracontyloxy-n-propylamine, 3-tetracosyloxy-n-propylamine, 3,3-dieicosyloxy-n-propylamine, 3,3-ditetracosyloxy-n-propylamine, 3,3-di-2-ethylhexyloxy-n-propylamine, 3,3-diisopropoxy-n-propylamine, 3-tert-butyloxy-n-propylamine and the like and mixtures thereof.

Methods for preparing the ether amines useful in the present invention are known. A most convenient method for preparing many of the ether amines and especially the more preferred ether amines is by hydrogenating the corresponding ether nitrile. The following equation illustrates this method of preparation

Any suitable hydrogenation catalyst can be used. Metallic catalysts commonly used are nickel, rhodium and the like. Raney nickel is an especially useful catalyst.

In addition to the primary amine which is the main product formed in this hydrogenation, the secondary amine $[\text{C}_2\text{H}_5-\text{O}-(\text{CH}_2)_4-\text{CH}_2]_2\text{NH}$ and some tertiary amine $[\text{C}_2\text{H}_5-\text{O}-(\text{CH}_2)_4-\text{CH}_2]_3\text{N}$ are also formed as products. The formation of the secondary and tertiary amines can be controlled or suppressed by using appropriate hydrogenation conditions, for example, by carrying out the hydrogenation process in the presence of ammonia. [See page 254, *Chemistry of Organic Compounds*, Carl R. Noller, 3rd Ed. (1965)].

A convenient method of preparing the more preferred ether nitriles for hydrogenation is by cyanoethylating suitable organic hydroxy compounds. A general discussion of this cyanoethylation reaction is found in "The Chemistry of Acrylonitrile," American Cyanamid Company (1951), and is incorporated herein by reference.

The cyanoethylation reaction is represented by the following equation:

Thus by choosing appropriate organic hydroxy compounds and preferably C_1-C_{40} monohydroxy primary alkanols, cyanoethylating them, then hydrogenating the resultant nitrile, the more preferred ethers of propyl amine can be prepared.

Besides using individual C_1-C_{40} alkanols such as methanol, n-dodecanol and the like, mixtures of the alkanols can also be used. These alkanol mixtures may simply be blends of individual alcohols; for example, 50 % $\text{C}_2\text{H}_5-\text{OH}$ / 50 % $\text{C}_3\text{H}_9-\text{OH}$; 2 % $\text{C}_{40}\text{H}_{81}-\text{OH}$ / 70 % $\text{C}_{20}\text{H}_{21}-\text{OH}$ / 20 % $\text{C}_{15}\text{H}_{31}-\text{OH}$ / 8 % $\text{C}_6\text{H}_{13}-\text{OH}$; 60 % 2-ethyl n-hexanol/ 40 % n-nonanol/ 33 % $\text{C}_{10}\text{H}_{21}-\text{OH}$ / 66 % $\text{C}_{12}\text{H}_{25}-\text{OH}$ and the like — or mixtures of useful alkanols can be cuts of or the entire product obtained from commercial processes such as the hydrolysis of aluminum trialkoxides produced by ethylene chain growth on trialkyl aluminum ("chain growth" alkanols). Particularly useful "chain growth" alkanols are those obtained from the process described in U.S. Pat. Nos. 3,415,861 and 3,384,651.

A particularly useful mixture of such "chain growth" alkanols has the following general composition. The mixture contains primary monohydroxy alkanols of both the linear and branch types. These mixtures are referred to as C_{10-12} mixed alkanols.

TABLE I

C_{10-12} Mixed Alkanols	
Number of Carbons	Weight %
$\text{C}_6 + \text{C}_8$	0 - about 10
C_{10}	about 25 - about 85
C_{12}	about 5 - about 50
C_{14}	0 - about 25
C_{16} and higher	0 - about 5

The following is a specific composition of a C_{10-12} type mixture. The weight ratio of linear:branched alkanols in the mixture is about 80:20.

TABLE II

Number of Carbons	Weight %
C_6-C_8	3.16
C_{10}	71.93
C_{12}	24.29
C_{14}	0.60
C_{16} and higher	0.02

Another class of preferred "chain growth" alkanol mixtures have the following general composition. Again, they are primary monohydroxy alcohols, both branched and linear with branched:linear weight ratios of 25:75 to 75:25, preferably 40:60 to 60:40. These mixtures are referred to as C_{20+} alkanols or alkanol mixtures.

TABLE III

C_{20+} Alkanols	
Number of Carbons	Weight %
C_{18}	0 - about 2
C_{20}	about 18 - about 45
C_{22}	about 15 - about 30
C_{24}	about 10 - about 20
C_{26}	about 10 - about 16
C_{28}	about 9 - about 14
C_{30}	0 - about 12
C_{32}	0 - about 9
C_{34}	0 - about 5
C_{36}	0 - about 2
C_{38}	0 - about 2
C_{40}	0 - about 1

Specific C_{20+} alkanol mixtures are presented in the following table.

TABLE IV

Number of Carbons	C ₂₀₊ Alkanol Mixtures (Weight %)				
	A	B	C	D	E
C_{18}	0.12	1.51	1.23	—	1
C_{20}	20.39	40.77	26.81	27.52	30
C_{22}	21.52	16.79	19.53	20.64	19
C_{24}	17.31	13.04	12.52	15.27	14
C_{26}	13.44	13.32	11.48	13.86	12
C_{28}	12.40	11.82	11.29	10.46	9
C_{30}	7.89	2.75	8.62	9.18	6
C_{32}	6.34	—	4.39	3.07	5
C_{34}	0.59	—	2.82	—	3
C_{36}	—	—	0.93	—	0.5
C_{38}	—	—	0.38	—	0.4
C_{40}	—	—	—	—	0.1

The following examples illustrate preparation of useful ether amines.

EXAMPLE 1

To a mixture of n-butanol (18.5 g, 0.25 mole) and 0.5 g of tetrabutyl ammonium hydroxide (25 percent in methanol) in a 100 ml flask was added acrylonitrile (14.3 g, 0.27 mole) so that the temperature did not exceed 35°. The mixture was stirred for 1 hour at ambient temperature (nitrogen atmosphere), neutralized with 2 ml of glacial acetic acid and distilled to give 35 g (96 percent yield, 100 percent conversion) of colorless liquid, bp 112°/35mm. Vapor phase chromatography (G.C.) analysis (12 feet × 1/4 inch) indicated the presence of a major peak (99 percent pure) with a retention time of 12.6 min. The infrared (IR) spectrum had

absorption at 2250 cm^{-1} ($-\text{CN}$) and at 1,110 cm^{-1} ($\text{C}-\text{O}-\text{C}$) and the nuclear magnetic resonance (NMR) spectrum showed two overlapping triplets (4H) centered at 3.60 δ and 3.48 δ corresponding to the protons adjacent to oxygen; a triplet centered at 2.55 δ (2H) corresponding to the methylene group adjacent to the nitrile. This characterizes β -butoxy propio nitrile.

Active Raney-nickel catalyst was prepared and about 3.5 grams were charged to a 250 ml stainless steel autoclave containing 80 ml of absolute ethanol, 11.7 g (0.092 mole) β -butoxy propionitrile and 8 g (0.45 mole) of liquid ammonia. The autoclave was charged with hydrogen (600 psig) and heated to 85°-95° with stirring. After 1.0 hr the autoclave was cooled, vented and flushed with nitrogen. The reaction mixture was filtered through Celite and distilled, bp 68°-69°/18 mm, to give 9.1 g of colorless liquid (75 percent yield, 100 percent conversion). Vapor phase chromatography analysis indicated one major peak (99 percent pure) having the same retention time as authentic γ -butoxy-propylamine [$\text{C}_4\text{H}_9-\text{O}-(\text{CH}_2)_3-\text{NH}_2$]. The pot residue from distillation was a solid material that was not characterized.

When primary alkanols, methanol, octanol, eicosanol, and $\text{C}_{20}\text{H}_{41}-\text{OH}$ and C_{20+} alkanols are used instead of n-butanol in the Example 1 process, the corresponding methoxy-, octyloxy-, eicosyloxy-, tetracontyloxy- and C_{20+} oxy-n-propylamines are obtained.

EXAMPLE 2

An autoclave was charged with 2.7 grams of a nickel-hydrogenation catalyst (Girdler T840B), and 80 ml of cyclohexane and heated at 75°-80°C. while hydrogen was sparged through the autoclave for about 1 hour. The autoclave was then cooled to 50°C. and 9.5 grams (0.07 mole) of β -butoxy propionitrile [$\text{C}_4\text{H}_9-\text{O}-(\text{CH}_2)_2-\text{CN}$] was added via a Hoke bomb by pressuring

with ammonia at 60 psig followed by hydrogen to 400 psig.

The mixture was stirred at 100°C. (pressure read 1,130 psig at 70°C., 1,200 psig at 95°C) for 2.5 hours. After 0.5 hour, the pressure had dropped to about 300 psig and hydrogen was added to give 400 psig at 100°C.

At the end of this time, the autoclave was vented and the reaction mixture was filtered. The catalyst residue was washed with ether and the washings were combined with the filtrate. The filtrate was then dried over calcium sulfate. The solvent was removed under vacuum and the residue was analyzed by gas chromatography. The analysis showed the product to be a mixture of

15 3% $\text{C}_4\text{H}_9-\text{O}-(\text{CH}_2)_2-\text{CN}$
65% $\text{C}_4\text{H}_9-\text{O}-(\text{CH}_2)_3-\text{NH}$
32% $[\text{C}_4\text{H}_9-\text{O}-(\text{CH}_2)_3+\text{NH}]$

This mixed product was separated by fractional distillation into the primary and secondary amine components.

This example illustrates that a mixture of primary and secondary amines can also be obtained on hydrogenating an ether nitrile. These mixed products may be used as such in gasoline or they can be fractionated into the individual components if desired.

Mixtures of ether amines contain the primary/secondary moieties in weight ratios ranging from 95/5 to 5/95. These mixtures may also contain from 0 to 5 percent by weight of the corresponding tertiary amine, which in Example 2 would have been $[\text{C}_4\text{H}_9-\text{O}-(\text{CH}_2)_3+\text{N}]$.

A method of preparing ether amines is also described in German Pat. No. 1,094,748, issued Dec. 15, 1960.

Following is a tabulation of ether amines obtained by hydrogenating ether nitriles, using the hydrogenation procedure illustrated by Examples 1 and/or 2.

Example	Ether Nitrile	Ether Amine Hydrogenation Product
3	$\text{C}_{20}\text{H}_{41}-\text{O}-(\text{CH}_2)_3-\text{CN}$	$\text{C}_{20}\text{H}_{41}-\text{O}-(\text{CH}_2)_3-\text{NH}_2$
4	$\text{C}_{10-12}\text{H}_{21-25}-\text{O}-(\text{CH}_2)_2-\text{CN}$	$\text{C}_{10-12}\text{H}_{21-25}-\text{O}-(\text{CH}_2)_3-\text{NH}_2$
5	$\text{n-C}_6\text{H}_{13}-\text{O}-(\text{CH}_2)_2-\text{CN}$	$\text{n-C}_6\text{H}_{13}-\text{O}-(\text{CH}_2)_3-\text{NH}_2$
6	$\text{C}_{10-12}\text{H}_{21-25}-\text{O}-(\text{CH}_2)_2-\text{CN}$	$\begin{cases} 20\% - \text{C}_{10-12}\text{H}_{21-25}-\text{O}-(\text{CH}_2)_3-\text{NH}_2 \\ 80\% - \text{C}_{10-12}\text{H}_{21-25}-\text{O}-(\text{CH}_2)_3-\text{NH}_2 \end{cases}$
7	$\text{n-C}_{12}\text{H}_{25}-\text{O}-(\text{CH}_2)_2-\text{CN}$	$\text{n-C}_{12}\text{H}_{25}-\text{O}-(\text{CH}_2)_3-\text{NH}_2$
8	$\text{C}_{24}\text{H}_{49}-\text{O}-(\text{CH}_2)_2-\text{CN}$ $\text{C}_{26}\text{H}_{53}-\text{O}-(\text{CH}_2)_2-\text{CN}$	$\begin{cases} \text{C}_{24}\text{H}_{49}-\text{O}-(\text{CH}_2)_3-\text{NH}_2 + \text{C}_{24}\text{H}_{49}-\text{O}-(\text{CH}_2)_3-\text{NH}_2 \\ \text{C}_{26}\text{H}_{53}-\text{O}-(\text{CH}_2)_3-\text{NH}_2 + \text{C}_{26}\text{H}_{53}-\text{O}-(\text{CH}_2)_3-\text{NH}_2 \end{cases}$
9	$\text{C}_{30}\text{H}_{61}-\text{O}-(\text{CH}_2)_7-\text{CN}$	$\text{C}_{30}\text{H}_{61}-\text{O}-(\text{CH}_2)_8-\text{NH}_2$
10	$\text{C}_6\text{H}_5-\text{CH}_2-\text{O}-(\text{CH}_2)_4-\text{CN}$	$\text{C}_6\text{H}_5-\text{CH}_2-\text{O}-(\text{CH}_2)_5-\text{NH}_2$
11	$\text{C}_{20}\text{H}_{41}-\text{O}-(\text{CH}_2)_2-\text{CN}$	$\begin{cases} 45\% - \text{C}_{20}\text{H}_{41}-\text{O}-(\text{CH}_2)_3-\text{NH}_2 + 55\% - \text{C}_{20}\text{H}_{41}-\text{O}-(\text{CH}_2)_3-\text{NH}_2 \\ \text{C}_{20}\text{H}_{41}-\text{O}-(\text{CH}_2)_3-\text{NH}_2 \end{cases}$
12	cyclohexyloxy-n-butyronitrile	$\text{C}_6\text{H}_{11}-\text{O}-(\text{CH}_2)_5-\text{NH}_2$
13	$\text{C}_{10-12}\text{H}_{21-25}-\text{O}-(\text{CH}_2)_2-\text{CN}$	$\begin{cases} 80\% - \text{C}_{10-12}\text{H}_{21-25}-\text{O}-(\text{CH}_2)_3-\text{NH}_2 \\ 20\% - \text{C}_{10-12}\text{H}_{21-25}-\text{O}-(\text{CH}_2)_3-\text{NH}_2 \end{cases}$
14	$\text{C}_{18}\text{H}_{35}-\text{O}-(\text{CH}_2)_2-\text{CN}$	$\text{C}_{18}\text{H}_{35}-\text{O}-(\text{CH}_2)_3-\text{NH}_2$

Example (cont) Ether Nitrile15 $C_{16}H_{33}-O-(CH_2)_2-CN$ $\longrightarrow \begin{cases} 40\% - C_{16}H_{33}-O-(CH_2)_3-NH_2 \\ 60\% - \underline{C_{16}H_{33}-O-(CH_2)_3} \underline{N} \end{cases}$ 16 $C_{12}H_{25}-\text{Cyclohexyl}-O-(CH_2)_2-CN$ $\longrightarrow C_{12}H_{25}-\text{Cyclohexyl}-O-(CH_2)_3-NH_2$ 17 $C_{20}H_{41}-O-(CH_2)_2-CN$ $\longrightarrow \begin{cases} 95\% - C_{20}H_{41}-O-(CH_2)_3-NH_2 \\ 5\% - \underline{C_{20}H_{41}-O-(CH_2)_3} \underline{N} \end{cases}$ 18 $C_{18}H_{37}-O-(CH_2)_2-CN$ $\longrightarrow \begin{cases} 45\% - C_{18}H_{37}-O-(CH_2)_3-NH_2 \\ 50\% - \underline{C_{18}H_{37}-O-(CH_2)_3} \underline{N} \\ 5\% - \underline{C_{18}H_{37}-O-(CH_2)_3} \underline{N} \end{cases}$ 19 $C_7H_{15}-O-(CH_2)_2-CN$ $\longrightarrow \begin{cases} 70\% - C_7H_{15}-O-(CH_2)_3-NH_2 \\ 30\% - \underline{C_7H_{15}-O-(CH_2)_3} \underline{N} \end{cases}$ 20 $30\% - C_{13}H_{27}-O-(CH_2)_2-CN$

The ether amines of the present invention are used in gasoline in concentrations ranging from about 5 to about 4000 parts per million by weight, preferably from 5-1,000 ppm, and more preferably from 20-100 ppm. Any gasoline suitable as a fuel for spark ignition internal combustion engines can be used. Gasoline is generally a blend of hydrocarbon having a boiling range of from about 25°C. to about 225°C, which occur naturally in petroleum; and suitable hydrocarbons made from petroleum by processes such as thermal and catalytic cracking, reforming, hydrocracking, polymerization and the like. Hydrocarbon compositions of typical base gasolines are given below; percentages are by volume.

25

EXAMPLE 24

25 ppm of a mixture of about 20% $C_{10-12}H_{21-25}-O-(CH_2)_3-NH_2$ / 80% $[C_{10-12}H_{21-25}-O-(CH_2)_3]_2NH$ was added to base gasoline A.

30

EXAMPLE 25

50 ppm of a 20% $C_{10-12}H_{21-25}-O-(CH_2)_3-NH_2$ / 80% $[C_{10-12}H_{21-25}-O-(CH_2)_3]_2NH$ mixture was added to base gasoline A.

35

EXAMPLE 26

To base gasoline A was added 25 ppm of $C_{20+}H_{41+}-O-(CH_2)_3-NH_2$.

TABLE V

Base Gasoline										
% of	A	B	C	D	E	F	G	H	J	K
Aromatics	29.0	28.5	30.0	50	—	—	60	80	38	16
Olefines	3.5	3.0	4.0	—	10	—	20	20	7	12
Saturates	67.5	68.5	66.0	50	90	100	20	—	55	72

In preparing the present gasoline compositions the ether amines may be added directly to the gasoline or they can be added as additive concentrates.

The following examples illustrate gasoline compositions of the present invention.

EXAMPLE 21

To base gasoline A was added 50 ppm of hexyloxy-n-propylamine.

EXAMPLE 22

A gasoline composition was prepared by adding 25 ppm of $C_{10-12}H_{21-25}-O-(CH_2)_3NH_2$ to base gasoline A.

EXAMPLE 23

To gasoline A was added 50 ppm of $C_{10-12}H_{21-25}-O-(CH_2)_3NH_2$.

Each of the Example 21-26 compositions also contained 3.16 grams of lead per gallon as tetraethyllead, about 1.44 grams of ethylene dibromide per gallon and about 1.52 grams of ethylene dichloride per gallon. The lead and halides were added as a commercial tetraethyllead fluid.

EXAMPLE 27

60 A series of gasoline compositions is prepared by adding 5, 200, 500, and 1,000 ppm of $C_{40}H_{81}-O-(CH_2)_4-NH_2$ to each of base gasolines A through H.

EXAMPLE 28

65 A series of gasoline compositions is prepared by adding 50, 60, 80 and 100 ppm of $CH_3-O-(CH_2)_8-NH_2$ to each of base gasolines B, F, and J.

EXAMPLE 29

4,000 ppm of

is added to base gasoline H.

EXAMPLE 30

A series of compositions is prepared by blending 8, 10, 30, and 150 ppm of each of Examples 1-20 ether amines in base gasoline C.

EXAMPLE 31

A series of compositions is prepared by blending 5, 25, 75, 400, 1,500 and 2,000 ppm of each of the following ether amines in base gasoline B:

In addition to the ether amines, the gasoline compositions can also contain other additives such as tetramethyl lead, (methyl cyclopentadienyl) manganese tricarbonyl, or iron pentacarbonyl; blending agents such as diisopropyl ether and acetone; anti-icers such as isopropanol, the carbitols; amines such as N-methyl aniline, aniline; deposit modifiers such as tris-(β -chloroisopropyl) thionophosphate, cresyldiphenyl phosphate, trimethyl phosphate, tricresylphosphate; metal deactivators such as N,N'-disalicylidene-1,2-diamino propane; antioxidants such as substituted phenylene diamines, 2,6-di-tert-butyl phenyl, 2,6-di-tert-butyl- α -dimethylamino-p-cresol; rust inhibitors, demulsifiers, dyes and the like.

Another embodiment of the present invention are additive concentrates of useful ether amines. These concentrates are blends of the ether amines in liquid carriers. The liquid carriers must be miscible with gasoline — and are preferably aromatic or aliphatic hydrocarbons and mixtures thereof. Typical liquid carriers are hexane, toluene, isoctane, xylene, benzene, heptane and the like. The ether amine additive concentrates can

contain from 10 — 90 percent by weight of the ether amine in a suitable liquid carrier. Use of a concentrate facilitates refinery blending of the additive into the gasoline.

5 Following are examples illustrating additive concentrates:

EXAMPLE 32

10 Concentrates are prepared containing 10 percent of each of the Example 1-20 ether amine in toluene.

EXAMPLE 33

15 A 90 percent Example 5 amine/ 10 percent hexane concentrate is prepared.

EXAMPLE 34

A 50/50 (by weight) blend of C₃₀H₆₁—O—(CH₂)₃—NH₂/decane is prepared.

EXAMPLE 35

20 A 70/30 (by weight) blend of Example 6 ether amine/isopropylbenzene is prepared.

EXAMPLE 36

25 A 40/60 (by weight) blend of Example 8 ether amine in benzene is prepared.

EXAMPLE 37

30 A concentrate containing 50 percent by weight of C₈H₁₇—O—(CH₂)₂—NH₂ in 50/50 (by weight) mixture of xylene/decane is prepared.

EXAMPLE 38

35 A concentrate containing 90 percent by weight of the Example 18 amine in mixed nonanes is prepared.

The ether amine additives of the present invention are effective carburetor detergents in gasoline. The following Carburetor Detergency Test was used to illustrate this effectiveness.

40 The carburetor of a standard 6-cylinder engine is fitted with a weighed split removable internal throttle-body sleeve. The engine is then operated on a cycle of 5 minutes idle, followed by 70-second part-throttle operation for a total of 2 hours. Blow-by is recycled through the carburetor. Following the test, the sleeve is removed and weighed. Results are reported in terms of percent reduction in deposits compared to that accumulated during operation of the engine for the same length of time but without the test additive.

45 50 Following are the detergency results obtained for gasoline compositions of the present invention.

TABLE VI

Carburetor Detergency				
Test	Gasoline Composition	Additive	Deposit Weight (grams)	Deposit Reduction
1	Base gasoline A	none	3.0 ¹	—
2	Commercial Detergent M ² in Base gasoline A	29 ppm	2.0 ¹	33 %
3	Example 21	50 ppm	2.3	23 %
4	Example 22	25 ppm	2.0	33 %
5	Example 23	50 ppm	1.7	43 %
6	Example 24	25 ppm	2.0	33 %
7	Example 25	50 ppm	1.4	53 %
8	Example 26	25 ppm	2.1	30 %

¹ Average of two runs.

² M is a commercial carburetor detergent.

The data clearly shows that the present ether amines are effective carburetor detergents.

The present ether amines can also be advantageously combined with intake valve deposit reducing additives, e.g., such as those described in U.S. Pat. No. 3,502,451. Especially useful intake valve deposit reducing additives are the 350-1,500 molecular weight liquid polymers of mixtures of C_{12} and higher olefins described in copending application Ser. No. 66,122, filed Aug. 21, 1970. The description therein is incorporated by reference.

These polymers are used in gasoline in concentrations ranging from about 400-2,000 ppm, and preferably below about 1,000 ppm. These use concentrations can be combined with the ether amine in the gasoline use concentration described herein. The combination of these additives then provides gasoline with enhanced intake system detergency.

Claims to invention follow.

I claim:

1. Gasoline containing a carburetor detergent amount of an ether amine having the formula $R-O-L-NH_2$ wherein R is C_1-C_{40} alkyl and L is C_2-C_8 alkylene.
2. The gasoline of claim 1 wherein R is C_4-C_{30} alkyl.
3. The gasoline of claim 1 wherein L is $-CH_2-CH_2-$.
4. The gasoline of claim 3 wherein R is C_4-C_{30} alkyl.
5. The gasoline of claim 4 wherein R is C_8-C_{24} .
6. The gasoline of claim 1 wherein R is a mixture of decyl and dodecyl.
7. The gasoline of claim 1 wherein R is derived from a mixture of C_{20+} alkanols.

UNITED STATES PATENT OFFICE
CERTIFICATE OF CORRECTION

Patent No. 3,849,083

Dated November 19, 1974

Inventor(s) Michael Dubeck

It is certified that error appears in the above-identified patent
and that said Letters Patent are hereby corrected as shown below:

In Column 2, lines 29-30 - that part of the formula reading
"-CH₂→CH₂₋₂" should read -- -CH₂-CH₂→- --

In Example 24, Column 8, lines 26-28 - that part of the two
formulae reading "-H₂₁₋₂₋₅-" should read -- -H₂₁₋₂₅ --

In Column 9, line 42 - "phenyl" should be -- phenol --

Signed and sealed this 4th day of March 1975.
